(57) **CLAIM**

The ornamental design for a headlight for a vehicle, as shown and described.

DESCRIPTION

FIG. 1 is a front left top perspective view of a headlight for a vehicle according to the present invention.

FIG. 2 is a front left perspective view of the headlight shown in FIG. 1.

FIG. 3 is a rear right top perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is another front view of the headlight shown in FIGS. 1-10, but mounted on a vehicle and with the rest of the vehicle shown in broken lines. The elements shown in broken lines form no part of the claimed design, but are instead included to show environmental aspects thereof. The claim includes a second embodiment which is a mirror image headlight on the opposite side of the vehicle.
